DOOR LOCK

Theodore Kanell, West Haven, Conn., assignor,
by mesne assignments, to Alexandria Kom-
paniez, Los Angeles, Calif.

Application December 24, 1949, Serial No. 134,963

11 Claims. (Cl. 292—169)

1

This invention relates to door latches and locks.

Doors are equipped with latch bolts that extend into a recess in a door jamb, the recess being framed by a striker plate. Such latch bolts are commonly urged by spring pressure into latching engagement with the striker plate. A knob or handle provides means for retracting the latch when it is desired to open the door.

It is now quite common to lock the door by preventing the latch from being withdrawn from the striker plate. In this type of lock, one of the principal advantages resides in the simplicity of installation. No intricate pattern nor deep slot need be cut in the door to provide a recess for a lock; instead simple drilling operations usually suffice for the installation of this type of door lock.

It is one of the objects of this invention to provide a combination door latch and lock of this character that is simple and inexpensive, and that is readily assembled for use in a door.

It is another object of this invention to make it impossible to remove the lock parts by disassembly of the mechanism unless the key is first used to unlock the door. In this way, access by an unauthorized person to the lock mechanism is effectively prevented.

Usually, removal of the lock mechanism from the door is effected by first removing one or both of the knobs or handles from the spindles. This can be done by urging a spring-pressed pin inwardly for releasing the knob. It is another object of this invention to prevent disassembly of the lock mechanism by ensuring that the pin cannot be moved to unlatching position until a key is used and moved to unlocking position.

In order to lock the door so that a key must be used exteriorly of the door to open it, a push button locking bolt operable from the inside is provided, which prevents operation of the knob on the exterior side of the door. It is another object of this invention to provide a simplified locking mechanism operating in this manner.

This invention possesses many other advantages, and has other objects which may be made more clearly apparent from a consideration of several embodiments of the invention. For this purpose there are shown a few forms in the drawings accompanying and forming part of the present specification. These forms will now be described in detail, illustrating the general principles of the invention; but it is to be understood that this detailed description is not to be taken in a limiting sense, since the scope of the invention is best defined by the appended claims.

2

Referring to the drawings:

Figure 1 is an elevation of a door locking mechanism embodying the invention, and shown as installed in a door, the door being shown in horizontal section;

Fig. 2 is a horizontal sectional view, on a somewhat enlarged scale, of the mechanism shown in Fig. 1;

Fig. 3 is a vertical section, taken along a plane corresponding to line 3—3 of Fig. 2;

Fig. 4 is a vertical section, taken along a plane corresponding to line 4—4 of Fig. 1;

Fig. 5 is a view similar to Fig. 4, but showing the latch grip and door latch in retracted or opening position;

Figs. 6, 7, 8, and 9 are vertical sectional views, on an enlarged scale, taken along planes corresponding to lines 6—6, 7—7, 8—8, and 9—9 of Fig. 3;

Fig. 10 is a fragmentary view similar to Fig. 2, but illustrating the latch bolt in locking position;

Fig. 11 is a fragmentary view of the latch bolt operating button in connection with the inner spindle, the button being shown in latch bolt releasing position;

Fig. 12 is a view similar to Fig. 11, but illustrating the latch bolt button in locking position;

Fig. 13 is a sectional view, taken along a plane corresponding to line 13—13 of Fig. 11;

Fig. 14 is an exploded pictorial view of the door latching mechanism;

Fig. 15 is a fragmentary view, similar to Fig. 2, of a modified form of latch bolt mechanism, the bolt being shown in released position;

Fig. 16 is a view similar to Fig. 15, illustrating the latch bolt in locking position; and

Fig. 17 is a sectional view, taken along a plane corresponding to line 17—17 of Fig. 16.

The door 1 (Figs. 1, 2, 3, and 4) is indicated as having a sloping edge 2 intended to cooperate with a door jamb opening formed by the door frame 3. A door latch structure has a cylindrical casing 4 (see, also, Fig. 14) which is accommodated in the usual manner in a horizontal bore 5 extending from edge 2 into the door 1. The latch bolt proper 8 is slidable within the casing 4. In this instance the latch bolt 8 carries a deadlatch 8^a that ensures against opening of the latch by urging the latch inwardly. The deadlatch structure is made the subject matter of another application.

Intersecting horizontal bore 5 is a transverse horizontal bore 6 which passes completely through the door 1, and which is large enough to accommodate a housing structure 7 (see Figs.

1, 2, 3, 4, and 14). This housing structure accommodates substantially all of the operating parts of the mechanism, as will be described hereinafter.

Latch bolt casing 4 is insertable into the bore 5, so that its inner end extends into the bore 6, as shown most clearly in Fig. 4. The left-hand end of the latch bolt casing carries a flange 9 which serves to support a plate 10 that is screwed to the edge of the door, as shown most clearly in Fig. 4.

When the door 1 is closed, the latch bolt 8 is projected through an aperture 18 formed in a striker plate 19 (Fig. 2). The striker plate 19 overlies a relatively deep recess 20 in the vertical edge of the door jamb 3. The latch bolt 8 and the striker plate 19 cooperate in the usual conventional manner, except for the deadlatch which engages the inner side of the plate 19 and is released only when the latch bolt is retracted.

After the latch bolt casing 4 is installed in the bore 5, the housing 7, with its operating parts, can be slipped into the bore 6 from the left-hand side, as viewed in Fig. 1. This housing 7 has a slot 11 at its left-hand side (Figs. 2, 4, 5, and 6) cut almost to the right-hand end of the housing, as shown most clearly in Figs. 1, 2 and 14.

The casing 4 for the latch bolt 8 has its inner end interrupted, to form the segments 12. On the exterior of these segments there are opposite slots 13 within which the edges of the slot 11 in the housing are accommodated as the housing 7 is moved toward the left, as viewed in Fig. 14. Thus the casing 4 and the housing 7 are kept in appropriate relative position.

The latch bolt proper 8 has an inner T-head 14 by the aid of which the latch bolt 8 may be retracted. The retracted position is indicated in Fig. 5. The mechanism for retracting the latch bolt 8 is enclosed in the housing 7.

As shown most clearly in Figs. 2, 4, and 5 the casing 4 has inwardly turned portions 15 that serve to hold the end wall for the casing in place.

In order to simplify the assembly and structure of the mechanism, the housing 7 is formed of two substantially semi-cylindrical parts 16 and 17 (Figs. 4 and 5).

Each of the sections 16 and 17 is provided with oppositely directed half hubs. Thus, section 16 has half hubs 21 and 22, while section 17 has the cooperating hubs 23 and 24. When the sections are placed together, these half hubs serve as bearings for operating spindles. These halves are held in cooperating position by the aid of a pair of cylindrical sleeves 25 and 26.

As hereinabove stated, the latch bolt proper 8 is retracted by the aid of the T-head 14. This T-head 14 is engaged by the latch grip 27 (Figs. 3, 4, and 14). This latch grip may be conventionally formed of sheet metal having oppositely directed jaws 28 that engage the head 14. In the inactive position of Fig. 4, these jaws extend through the slot 11 of the housing section 16.

The remainder of the latch grip 27 is formed in a rectangular box-like manner. Its side walls are guided by the projections integrally formed on the end walls of the housing members 16 and 17. These projections are shown to best advantage in Figs. 4, 5, 6, and 7.

Thus, the housing section 16 is provided with the integrally formed bosses 29 and 30 opposing the outer side of the wall of the latch grip 27. An integrally formed guide 31 is opposed to these two guides 29 and 30 to cooperate with the inner surface of the latch grip.

Similarly arranged integral guides 32 and 33 are disposed on the section at the opposite side of the latch grip. The guide 34 on section 17 cooperates with these guides 32 and 33 to form a guide for the opposite wall of the latch grip 27.

The latch grip 27 is adapted to be urged resiliently toward the position shown in Fig. 4, in which the latch bolt 8 is in locking position. For this purpose, the inner wall 35 of the latch grip has an aperture guided on a stationary post 36 (see, particularly, Figs. 2, 4, 5, and 14). This post has a head 37 against which the outer wall of the latch grip is urged by the compression spring 38. This compression spring surrounds the post 36.

The post 36 may be conveniently attached to the housing section 17, as, for example, by the aid of the screw 39.

The mechanism for moving the latch grip 27 to the opening position of Fig. 5 may now be described. Stamped out of the opposite sides of the latch grip 27 are the inwardly directed projections 40. These extend toward each other and are spaced sufficiently apart so that the head 37 of post 36 will not interfere with the inward movement of the latch grip 27.

An outer spindle 41 is rotatably supported within the half hubs 21 and 23 (see, particularly, Figs. 2, 3, and 14). Radial projections 42 extend externally of this spindle and engage the end wall of the housing 7 to prevent outward movement of the spindle 41. Inward movement is prevented in a manner to be hereinafter described.

The spindle 41 is hollow, and a part of it is removed at the inner end in order to form a segmental configuration, closed by the end flange or segmental wall 43.

The edges 44 (Figs. 4 and 14) of this end overlie the inwardly directed projections 40. In the normal position of Fig. 4, the spindle 41 is in the inactive position. Now, by turning the spindle 41 in either direction, either one or the other edge 44 of the segmental portion 43 operates on one or the other of the inwardly directed flanges 40 of the latch grip 27. Thus, as shown in Fig. 5, if the spindle 41 be rotated in a counter-clockwise direction, as viewed in that figure, the lower corner of the segmental wall 43 engages the lower projection 40, urging the latch grip toward the right and compressing the spring 38. This causes retraction of the head 14 and corresponding retraction of the latch bolt 8. Obviously, a similar action is produced when the spindle 41 is rotated in a clockwise direction.

The spindle 41 is adapted to carry a knob structure 45. This knob structure may be of any conventional type, having a tubular projection 46 which telescopes over the spindle 41. The right-hand end of this projection 46 is arranged to abut the ring 25 and the hub sections 21 and 23. A locking pin 47, for example (see, particularly, Figs. 2 and 8), couples the spindle 41 with the extension 46 as by passing through aligned apertures therein. This pin 47 is mounted on a flat spring 48 attached to the spindle 41 near its inner end. Normally this spring holds the coupling pin in projected position.

The spindle 41 has a slot 49 at its upper side. This slot 49 is widened at its outer end to form an outer slot 50. This slot, as shown most clearly in Fig. 3, accommodates a vane 51. This vane 51 serves to position a cylindrical lock 52 at the end of the spindle 41. This lock 52 carries an operating member 53 that can be rotated only when a key, such as 54 (Fig. 1), is inserted into a key-

hole in the end of the cylindrical lock 52. Otherwise, as will be explained hereinafter, turning of the key 54 will serve to move the latch grip 27 to opening position.

Thus, the operator 53 (see, especially, Figs. 6 and 8) is accommodated in a slot 55 formed in the outer end 56 of the key spindle 57. This key spindle is rotatable within the outer spindle 41 and is spaced from the outer spindle 41 by the aid of the spacer projections 58 formed on the inside of the spindle 41. When the key 54 is inserted in the lock 52, the operator 53 is turned. In turning, this operator causes the inner segmental end 59 of the spindle 57 to depress the projections 40 of the latch grip 27. This inner segmental end 59 of the key spindle 57 extends to the segmental end wall 43 of spindle 41. As shown most clearly in Fig. 2, it overlies the inwardly directed projections 40. This inner key spindle 57 is also shown in Fig. 10.

When the key 54 is used, the knob 45 may remain stationary, since only the operator 53 is moved by operation of key 54. However, when the knob 45 is turned without use of the key 54, the lock 52 is bodily turned, due to the coupling between vane 51 and slot 50. In this way, the segment 59 of the key spindle 57 will be rotated by operator 53, and will permit outer spindle 41 to open the latch.

The inner spindle 60 is rotated similarly to spindle 41 within the half hubs 22 and 24. It is provided with the outwardly directed projections 61 engaging the inner surface of the wall of casting 7 to prevent outward movement of the spindle 60. As shown most clearly in Figs. 2 and 10, the inner ends of the spindles 41 and 60 approach quite closely together substantially at the center of the housing 17. Thus, these ends prevent material inward movement of the spindles.

The inner end 62 of the spindle 60 is cut away to form a segment. This segment is adapted to engage the projections 40 of the latch grip 27. Accordingly, by rotation of the inner spindle 60 in either direction, the latch 8 may be retracted.

A knob structure 63 telescopes over the spindle 60 and may be held detachably in place by the aid of a coupling pin 64 (Figs. 2 and 9). This coupling pin 64 is carried by a flat spring 65 attached near the outer end of the spindle 60.

The assembly of the parts, as thus far described, is apparent from the foregoing. The outer and inner spindles 41 and 60 are placed between the halves 16 and 17 of the housing 7. The rings 25 and 26 are then slipped over the hubs 21—23 and 22—24 of the housing 7 to hold the two parts of the housing together. Before the knobs 45 and 63 are disposed over the spindles, the rosettes 66 and 67 are passed over these rings. These rosettes carry the attaching plates 68 and 69 overlying the bore 6 in the door. As shown most clearly in Figs. 3, 4, 5, and 6, spacer posts 70 are attached to the attaching plate 68 and pass through the housing sections 16 and 17. These posts are internally threaded for the accommodation of the screws 71 passing through the attaching plates 69. Rosettes 66 and 67 serve to conceal these screws. As the axial length of the housing 7 is substantially less than the width of the door 1, spacers may be introduced between the attaching plates and the outer wall 70 of the housing 7.

The outer knob 45, as heretofore stated, is held in place on the outer spindle 41 by the aid of the coupling pin 47. It is possible, of course, to disassemble to the entire lock structure by 75

urging the pin 47 inwardly against the resilience of the spring 48 by an appropriate instrument, and thereafter removing knob 45 and operator 53.

By the present arrangement, inward movement of the pin 47 is prevented, thereby preventing such removal of the knob 45 unless the key 54 is in the opening position. For this purpose, the spring 48 carries an inwardly turned end 72 (Figs. 2 and 8). This inwardly turned end 72 closely approaches the edge of the operating member 53. While this operating member 53 is in the locking position, the pin 47 cannot be urged inwardly. When the operating member 53 is turned, by aid of the key in the lock 52, the spring 48 is unimpeded and the parts may be disassembled.

Provisions are made for locking the outer spindle 41 against rotation, thereby making it necessary to use key 54. This locking effect can be such that the key spindle 57 can nevertheless be operated by the key.

The locking mechanism for the spindle 41 is shown to best advantage in Figs. 2, 3, and 10. As shown most clearly in Fig. 4, the head 37 of the post 36 is slotted. The slot in this head is in alignment with a slot 73 of the segmental wall 43 of spindle 41. Accordingly, in order to prevent rotation of the spindle 41, a locking bolt 74 can be moved so as to be interposed between these two slots. Such a locking bolt 74 is arranged to be slidable within the inner spindle 60. It has a projection 75 that is in continual guiding relation with the slot in the head 37. This bolt 74 has a wider portion 76 which extends downwardly so as to be engaged in the slot 73 when the bolt 74 is moved toward the left, as shown in Fig. 10. In this position, the bolt 74 now acts as a lock to prevent rotation of spindle 41 with respect to the head 37. This bolt does not engage the key spindle 57 and, therefore, there is no restraint against opening of the door by the use of the key 54.

The sliding bolt 74, as shown most clearly in Fig. 7, is quite flat and extends in a horizontal direction. It is provided with a shank portion 77 (see, also, Fig. 9) to which is rotatably connected a push button 78 that is slidable in the open end of the spindle 60 (Figs. 11, 12, and 13). A washer 79 surrounds the stem 77 and is abutted against an interrupted flange 80 formed on the inner surface of the spindle 60. In the assembled position of Figs. 2 and 10, the washer 79 serves as an abutment for the left-hand end of a compression spring 81. In the unlocked position of Fig. 2, the push button 78 is urged by the spring 81 to its extreme right-hand position, indicated in Fig. 11. When it is desired to lock the outer spindle 41, the push button 78 is urged inwardly to assume the position of Fig. 10. The corresponding inward movement of the bolt 74 operates to lock the spindle 41.

The push button 78 may be retained in the locked position by the aid of a projection 82 (Figs. 11, 12, and 13) which is accommodated in a slot 83 at the end of the spindle. This slot 83 extends in an axial direction and connects with an arcuate slot 84 formed in the spindle 60. At the end of this arcuate slot, as shown most clearly in Fig. 11, a seat 85 is provided for the projection 82. In this way the button 78 may be rotated so as to bring the projection 82 into the seat 85 to retain the lock 74 in locking position. Spring 81 urges projection 82 into the seat 85. In order to release the lock, the push button

78 may be pressed slightly inwardly to raise the projection **82** from the seat, and then it may be turned to the position of Fig. 11. The spring **81** then urges the push button **78** outwardly and also urges the lock **74** to the releasing position of Fig. 2.

The button **78**, of course, is so mounted that it is freely rotatable with respect to the stem **77** of lock **74**.

Since the push button **78** must be urged inwardly to a position where it may drop into seat **85**, the bolt **74** must travel somewhat past its locking position. In order to permit the bolt to pass temporarily to that position, the inner end of the key spindle **57** has a slot **88**.

The bolt **74**, with the washer **79**, spring **81**, and push button **78** may be first assembled with the spindle **60** before the spindle **60** is assembled with the housing **1**. The bolt **74** has a wide portion **87** which engages the flange **89**, limiting expansion of the spring. Removal of the lock **74** is also prevented with respect to spindle **60**. However, by turning the lock **74** through a ninety degree angle, the wide portion **87** can pass through the slots **88** formed between the interrupted flange portions **80**. Thus, the entire bolt assembly may be removed.

It is noted, in Fig. 9, that the washer **79** has a flattened side **89**, permitting space for the spring **65** that urges the coupling pin **64** outwardly. In this way, the washer **79** may be inserted without interference.

In the form of the invention illustrated in Figs. 15, 16 and 17, the locking bolt **90** is assembled with a push button **91** which does not need to be turned in order to hold the locking bolt in locked position. For this purpose, a hairpin spring **92** is provided which, as shown in Fig. 17, straddles the locking bolt **90**. The ends of this hairpin spring are formed into loops for the accommodation of attaching rivets which pass through the locking bolt **90**.

The free upper end of the hairpin spring is urged resiliently against the inner wall of the inner spindle **93**. When the button **91** is urged inwardly, this upper free end of the spring slips into a restraining aperture **94**. The end of the spring **92** is thus retained in place in the locking position.

The bolt **92** may be permitted to return to the unlocked position by the aid of a slight rotation of the inner spindle **93**. The end edges of the elongated aperture **94** act as cams upon rotation of the spindle **93** to urge the hairpin spring **92** inwardly. As soon as a slight rotation is effected, the hairpin spring is urged out of the opening **94**, and the spring **81** urges the locking member **90** to the open position.

The inventor claims:

1. In a device of the character described: a pair of hollow generally half-cylindrical members, said members cooperating to form a pair of hollow bearing hubs on opposite ends of said members, each of said members forming one opposed half respectively of each bearing hub; an inner spindle rotatable in one hub; an outer spindle rotatable in the other hub; and means maintaining said members in assembled position.

2. In a device of the character described: a pair of hollow generally half-cylindrical members, said members cooperating to form a pair of hollow bearing hubs on opposite ends of said members, each of said members forming one opposed half respectively of each bearing hub;

an inner spindle rotatable in one hub; another spindle rotatable in the other hub; and sleeves respectively engaging the hubs for maintaining the members in assembled position.

5. In a door latch structure cooperable with a latch grip: a housing formed of a pair of hollow generally half-cylindrical members, said members cooperating to form a pair of hollow bearing hubs on opposite ends of said housing, each of said members forming one opposed half respectively of each bearing hub; means detachably securing the members together; an inner spindle rotatable in one hub; and an outer spindle rotatable in the other hub; said members including parts providing a sliding guide for said latch grip.

4. In a door lock mechanism: a housing; a latch grip movably mounted in the housing; a first rotatable spindle extending into one side of the housing for operating the latch grip; a second rotatable spindle extending into the housing at the opposite side thereof; a lock bolt longitudinally movable in the second spindle cooperating with the first spindle to restrain said first spindle from rotating; means urging the bolt in releasing direction; and a spring detent carried by the bolt and having a projection adapted to engage a recess in the second spindle for holding the bolt in locking position; said spring detent being urged to disengaging position by the edge of the recess when the said second spindle is rotated.

5. In a door lock mechanism: a housing; a latch grip movably mounted in the housing; a first rotatable spindle extending into one side of the housing for operating the latch grip; a second rotatable spindle extending into the housing at the opposite side thereof; said first spindle having a slot; a lock bolt longitudinally movable in the second spindle; a stationary guide for the bolt; said bolt when moved inwardly being engageable in said slot for locking said first spindle; means urging the bolt in releasing direction; and a spring detent carried by the bolt and having a projection adapted to engage a recess in the second spindle for holding the bolt in locking position; said spring detent being urged to disengaging position by the edge of the recess when said second spindle is rotated.

6. In a door lock mechanism: a housing; a latch grip movably mounted in the housing; a first rotatable spindle extending into one side of the housing for operating the latch grip; a second rotatable spindle extending into the housing at the opposite side thereof; said first spindle having a slot; a lock bolt longitudinally movable in the second spindle; a stationary guide for the bolt; said bolt when moved inwardly being engageable in said slot for locking said first spindle; means urging the bolt in releasing direction; and a spring having legs straddling the lock and fastened thereto, said spring also having a free end engageable in a recess in the second spindle for holding the bolt in locking position; said spring being urged to disengaging position by the edge of the recess when said second spindle is rotated.

7. In a door latch mechanism: a housing; a headed post extending transversely of the housing and fixed to a wall of the housing; a latch grip slideable in said housing, said latch grip having a guiding aperture accommodating said post, the head of the post limiting movement of the latch grip in one direction; a spring surrounding the post and urging the latch grip against said

head; a rotatable spindle having a part engaging the latch grip for urging the latch grip away from the head; said part and the head of the post having aligned slots when the latch grip is in engagement with the head; and a lock bolt carried by the housing and selectively movable to engage both said slots to prevent rotation of said spindles.

8. In a door latch mechanism: a housing; a headed post extending transversely of the housing and fixed to a wall of the housing; a latch grip slidable in said housing, said latch grip having a guiding aperture accommodating said post, the head of the post limiting movement of the latch grip in one direction; a spring surrounding the post and urging the latch grip against said head; a first rotatable spindle having a part engaging the latch grip for urging the latch grip away from the head; said part and the head of the post having aligned slots when the latch grip is in engagement with the head; a lock bolt for engaging said slots; and a second rotatable spindle extending in a direction opposite to the first spindle, said lock bolt being supported in said second spindle.

9. In a door latch mechanism: a two-part generally cylindrical housing; a headed post attached to the interior of one of the parts of the housing and extending toward the other part; a latch grip guided by the housing for sliding movement from one cylindrical wall to the other, and having a guiding aperture accommodating said first post, the head of the post limiting movement of the latch grip; a compression spring surrounding the post and urging the grip against said head; a first rotatable spindle extending axially of the housing and into the housing, said spindle having projections limiting outward movement of the spindle; said first spindle also having an inner end engaging the latch grip which upon rotation of the first spindle serves to move the latch grip away from the head; a second rotary spindle extending axially of the housing in a direction opposite to the direction of the first spindle, said second spindle having projections limiting outward movement of the spindle; said second spindle having a latch grip operating inner end serving upon rotation of the second spindle to move the latch grip away from the head; the ends of the spindles being closely spaced to limit inward movement of the spindles with respect to the housing; the end of the first spindle and the head having aligned

slots when the latch grip is in engagement with the head; and a lock bolt slidable in the second spindle for engaging said slots.

5 10 15 20 25 30 35

10. In a door latch mechanism: a housing; a post extending transversely of the housing and fixed to a wall of the housing; a latch grip slidable in said housing, said latch grip having a guiding aperture accommodating said post; means forming an abutment limiting movement of the latch grip in one direction; a spring surrounding the post and urging the latch grip against said abutment forming means; a first rotatable spindle having a part engaging the latch grip for urging the latch grip away from said abutment forming means; said part and said post having slots that are aligned when said latch grip is in engagement with said abutment forming means; a lock bolt for engaging said slots; and a second rotatable spindle extending in a direction opposite to the first spindle, said lock bolt being supported in said second spindle.

11. In a door latch structure: a hollow generally cylindrical housing split along an axial plane and provided with bearing hubs on opposite ends of said housing; spindles respectively rotatable in said hubs and extending outwardly of the housing; said spindles each having radially extending parts preventing removal of the spindles from the housing; and a pair of sleeves telescopingly received by the hubs respectively for maintaining the members in assembled position.
